UNITED STATES PATENT OFFICE.

ALBERT P. WAGNER, JR., OF DETROIT, MICHIGAN.

CEMENT FORM.

Application filed June 6, 1924. Serial No. 718,207.

The object of my invention is to provide new and useful improvements in a cement form of simple, durable, and inexpensive construction.

5 A further object of my invention is to provide a multiple block mold by which a plurality of concrete blocks may be made at the same time in the same mold.

10 A further object of my invention is to provide a multiple block mold which is particularly adapted for making slush concrete blocks as distinguished from the blocks made by the semi-dry method.

15 A further object of my invention is to provide a multiple block mold having collapsible cores by which the blocks may be made with hollows or air passages therein conveniently and expeditiously.

20 A further object of my invention is to provide a peculiar type of core which will collapse or expand in the direction of both transverse dimensions.

25 A further object of my invention is to provide a multiple block which is so constructed that the individual blocks made thereby may be formed on independent pallets so that the blocks may be conveniently handled after being removed from the molds and during the period that they are being seasoned.

30 With these and other objects in view, my invention consists in the arrangement, combination, and construction of the various parts of my improved device, as described in the specification, claimed in my claim, and shown in the accompanying drawings, in which:

Figure 1 shows the top or plan view of my improved multiple mold.

40 Figure 2 shows an end view thereof.

Figure 3 shows an elevation of one of the partitions therefor.

Figure 4 shows an elevation of the collapsible core.

45 Figure 5 shows an end view of the collapsible core shown in Figure 4.

Figure 6 shows an elevation of the partition members used to form the ends of the blocks.

50 Figure 7 shows an end view of the partition member illustrated in Figure 6.

Figure 8 shows a type or plan view of the pallet upon which the blocks are formed.

55 Figure 9 shows an end view of the pallet shown in Figure 8, and

Figure 10 shows a perspective view of the

block which I desire to form with my multiple mold.

Referring to the accompanying drawings, I have shown the multiple mold as being 60 mounted on a truck having a platform 10 which in turn is mounted on a truck having wheels 11 designed to run on rails 12 and provided with side members or stakes 13. The stakes 13 at one side of the truck are beveled on their inner surface to coact with wedges 14 whereby the mold members may be wedged together on the truck during the time the concrete is being poured to form the blocks. The mold itself consists 65 of a plurality of longitudinal partitions 15 which are held in position spaced from each other by a plurality of transverse partition members 16. These transverse members 16 have tongues 17 at one end and pockets 18 70 at the other end whereby the tongue 17 may be passed through the slots 19 in the longitudinal partition members 15 to anchor the transverse member 16 from movement 75 relative to the longitudinal partition members 15 or from movement relative to each other.

The transverse partition members 16 are preferably formed from three superimposed strips of sheet metal which have their edges 80 fastened together by the countersunk rivets 20 or preferably by spot welding so that their surface may be smooth. The central portions of the outer strips are bowed or dished at 21 to form the concave end portions 22, 90 illustrated in Figure 10. The central strip is formed to make the tongue 17 and the pocket 18. The longitudinal members 15 have a plurality of pairs of adjacent openings 23 therein so that when the longitudinal and transverse members are assembled 95 together then the collapsible core members shown in Figure 4 may be passed through these openings 23 to form the core for making the openings 24 through the block as 100 illustrated in Figure 10. These core members are formed primarily from four strips of sheet metal which are initially in the shape of substantially a parallelogram and which are folded adjacent to each edge to 105 form a flange 25. One flange of each strip is provided with a pair of slots 27 and the other flange is provided with a pair of buttons 28 so that when the four strips are folded on a diagonal line substantially bisecting the strips, then that the buttons on one flange will enter the slots in the flange

of the adjacent strip to form the rectangular core illustrated in Figures 4 and 5. It will be seen that this core may be expanded or contracted by sliding the strips upon each other as the buttons 28 will move in the slots 27 to permit this sliding movement of the flanges relative to each other. The blocks formed by this mold each set on an independent pallet member, such as is illustrated in Figures 8 and 9 wherein a strip of sheet metal 29 is provided and a pair of angle irons 30 which are secured to the lower surface thereof by a plurality of countersunk rivets 31 or preferably by spot welding.

In the practical operation of my improved device the mold is assembled on the truck member by first placing one longitudinal member 15 against the stakes 13 at one side of the truck which have the vertical inner surfaces. A row of transverse members 16 is then placed against this first longitudinal member 15 and the pallets 29 for the first row of blocks are then placed on the truck. A second longitudinal member 15 may now be assembled on the projecting tongues 17 of the transverse members and a second set of transverse members 17 and pallets 29 placed on the truck. This process is continued until the entire five rows of molds are completed and then when the last longitudinal member 15 is installed, wedges 14 may be driven down between the stakes 13 having the inclined inner surfaces and the last longitudinal member 15 to lock the mold from movement. The core members illustrated in Figures 4 and 5 may now be installed by collapsing these core members and inserting them in the holes 23 in the longitudinal members. After being placed in these holes the core members are expanded by pounding the ends thereof until all four sections thereof are properly seated against the openings 23.

Slush concrete may now be poured over the mold to fill the various block forms therein and if desired the concrete may be rolled or tamped to initially set same. In

a very short time the wedges 14 may be removed to loosen the form and the cores tapped to collapse them so that they may be withdrawn from the mold. As soon as the cores are withdrawn and the wedges 14 removed then the mold may be disassembled in the manner in which it was assembled. It will be noted in this connection that the pallets 29 are spaced up from the bottom 10 of the truck member so that they may be readily lifted therefrom to be placed on other trucks or suitable platforms for seasoning.

With this improved mold I am able to make slush concrete blocks satisfactorily and with reasonable economy with the well known advantages of slush concrete as compared with the semi-day method of making cement blocks.

Among the many advantages arising from the use of my improved mold it should be specifically pointed out that the mold itself is constructed from sheet metal which may be readily purchased in the open market and very little forming or cutting of the metal is required in order to form these molds. Moreover the mold is easily assembled and disassembled, is comparatively simple, and the danger of cracking or injuring the completed blocks at the time of disassembling is comparatively slight.

I claim as my invention:

In a mold for a plurality of concrete blocks, a plurality of spaced longitudinal members having spaced slots therein and a plurality of transverse members each composed of three strips of sheet metal, the outer strip being bowed to form corresponding hollows in the blocks and the central strips having tongues formed at one end and pockets formed at the other end whereby said tongues may enter the slots adjacent thereto in the longitudinal members and the pockets in the adjacent transverse members to thereby lock the longitudinal members from movement relative to each other and relative to the longitudinal members.

ALBERT P. WAGNER, JR.
